SWIVELED DRILL BIT FOR CABLE TOOL
DRILLING

Elgan S. Sloan, Shippensburg, Pa.

Application October 14, 1931, Serial No. 568,842

5 Claims. (Cl. 255—72)

This invention relates to improvements in drilling apparatus, more particularly in drill bits for use in connection with cable tool drilling rigs, and the objects of the invention are as follows:—

5 First, to provide a reciprocating drill with a bit and carrier each having matching shoulders above and below an interposed ball annulus so as to confine the major impact to the shoulders and guarding the balls against possible shearing 10 and the edges of the races against possible chipping, said ball annulus further providing a swivel mount for the bit.

Second, to provide the drill bit both with an internally shouldered structure and a down- 15 wardly tapering bore for the respective purposes of establishing a rest or ledge for the support of the fragments of the core and for the establishment of an annular wedge space around the cylindrical core, said space when becoming im- 20 pacted with fragments enabling the fragments and the tapering walls of the bore to operate as a combined gripper against the core so as to break it off and enable bringing it to the surface when the drill is extracted from the hole.

25 Other objects and advantages will appear in the following specification, reference being had to the accompanying drawing, in which

Figure 1 is a vertical section of a cable drilling tool particularly illustrating the swiveled drill 30 bit which is the principal subject of this invention,

Figure 2 is a partial inverted plan view of the swiveled cutting bit particularly illustrating the peculiar type of teeth which not only embody 35 cutting edges but also constitute the means whereby turns are automatically imparted to the cutting bit when the bottom of the well hole is impacted,

Figure 3 is a fragmentary elevation of the drill 40 bit, again illustrating the foregoing teeth.

The foregoing objects of the invention are carried out in the following structure, particular reference being first made to Figure 1:—The lowermost end section 1 of tubing or other sus- 45 pending device which may be regarded as of any length, has an internally threaded portion 2 into which a filler 3 is screwed. This filler includes an annular flange 4, the top surface 5 of which will bear tightly against the bottom end 6 of the section 1 when the filler 3 is screwed home.

It is a matter of choice whether or not the joint at the place 5, 6 shall be welded as at 7. Ordinarily, for the sake of security, the joint will be welded thus precluding any possibility of the 55 filler 3 loosening while the drill is in operation.

In practice the filler 3 will preferably be made of a tough variety of steel primarily to prevent its showing any fault during the strenuous service to which it is subjected. It is to be observed that the bottom surface 8 of the flange 4 is considerably wider than the top surface 5. This is, of course incidental to the construction of the filler 3, but the fact of the surface 8 being wider than the surface 5 has the following important advantage:—

The end 6 of the tubing 1 is comparatively narrow. If the thrusts of the drilling operation were imposed directly on the bottom end 6 there is the possibility of the bottom spreading or becoming bruised. By interposing the filler 3 and especially the annular flange 4 with its wide surface 8 there is considerably more area over which the impacts of the tool can be distributed, thus guarding the bottom end 6 of the tubing 1 from the dangers mentioned.

Inside of the filler 3 there is what is herein known as a carrier 9 inasmuch as it carries the cutting bit 10. The carrier 9 is externally threaded to be screwed home in the internally threaded filler 3, and when screwed home the top surface 11 of a head 12 makes a very tight contact with the foregoing bottom surface 8 of the flange 4. The so-called head 12 is virtually an annular flange similar to the flange 4, but the distinction is made because of the larger proportions of the head 12.

The bottom end structure of the carrier 9 includes shoulders 13, 14 and a connecting vertical wall 15 in which half 16 of a ball race is formed. The complementary half 17 of this race occurs in 90 the cutting bit 10 which has shoulders 18, 19 and a vertical wall 20 matching the corresponding parts of the head 12.

A ball annulus 21 occupies the race 16, 17. The balls are introduced through a side opening 22 which is later plugged by a screw 23 or its equivalent. The ball annulus is much on the order of any ordinary ball bearing although it does not include a cage. The chief purpose of the balls is to act as keys between the carrier 9 and cutting bit 10, sole dependence being put on these balls to prevent the dropping away of the cutting bit from its carrier means 9. The balls simultaneously provide a swivel mount for the bit and lock it in place on the carrier 9. The term "lock" means prevention of endwise movement only.

So far it will be understood that the drill bit assemblage, generally denoted 24 comprises what might be called a stage construction, that is to say, comprises a plurality of parts which fit into

each other, and in being fitted into each other are so made that one part depends upon the next for its support not only while that part is intact but also in the event of its having become cracked.

5 This is best understood by considering the cutting bit 10 first. Suppose the cutting bit were split in half vertically. There would be no possibility of the parts dropping out because of the key function that the balls 21 perform. It is 10 even conceivable that the cutting bit 10 would continue performing this function properly even though split vertical into two or more fragments.

The same principle of holding together applies 15 to the carrier 9 and filler 3. In the event of the carrier 9 becoming split its threaded engagement inside of the filler 3 would hold the parts together. In the event of the filler 3 becoming split the internal threaded portion 2 of the tubing 1 20 would again hold the parts together. It is the fact of these various components being successively secured inside of each other that insures the holding together of the broken parts in the event that a breakage occurs.

25 The cutting bit 10 is provided with teeth 25, 25^a of a peculiar formation. The bezel 25^b of each tooth stands on a decided incline in one direction as clearly shown in Figure 3. The inclination may be in one or the other direction, 30 but the specific inclination in Figure 3 is chosen because the reaction of the teeth against the solid substances at the bottom of the well hole will cause a reaction in the direction of the arrow 26 (Fig. 3), this being a clockwise direction to 35 agree with the threads of the carrier 9 and filler 3 which are herein regarded as being right-handed.

From the foregoing statement it will be understood that incidental dependence is put on 40 the shape of the teeth 25 in keeping the carrier 9 and filler 3 screwed up tight. Of course, in the event that the joint 5, 6 is welded at 7 there would be no possibility of the filler 3 unscrewing from the tubing section 1, but the carrier 9 will 45 not ordinarily be welded in place and therefore the foregoing reaction of the teeth 25 is an important aid to keeping the carrier 9 in place.

Each tooth 25, 25^a includes a component 27 which generally falls in the zone 28^a (Figs. 1 and 50 3). This component is angled both in respect to the longitudinal and transverse axes of the drill bit. It is this component that virtually establishes the inclination of the teeth as will be noted by tracing the direction of the teeth from 55 the bottom of the zone 28^a. Alternate ones of the teeth 25 extend farther under the rounded terminal 28 of the cutting bit 10 (Fig. 1) than the intermediate teeth 25^a, the former ending at points 29 (Fig. 1) which, when considered collectively in the circumferential direction, constitute the boundary of a bottom opening in the cutting bit 10 communicating with the flaring bore 30 which occurs both in the cutting bit 10 and the carrier 9. This bore when considered from 60 65 the other direction, that is to say reading down from the top, is downwardly tapering, and is intended to perform a very important function as will presently be brought out.

70 Alternate ones 25^a of the cutters extend inwardly under the rounded terminal 28 a lesser distance than the cutters 25 as denoted at 29^a to provide unobstructed courses for the up flowing liquid. The inner walls 29^b of teeth 25^a merge with the otherwise solid walls 29^c of that 75 portion of the bore 30 occurring in the bit 10.

The teeth 25 extend inwardly a little farther than teeth 25^a as at points 29 whence they taper to points of mergence with the bore 30. The portions 29^d of teeth 25 extend inwardly beyond the walls 29^b of the teeth 25^a and serve as cutters 80 or shears.

All of the teeth 25, 25^a have extensions 31 under the body of the cutting bit as already brought out, these extensions being provided with cutting edges 32 backed up by the bezel 25 in each instance, which edges do the major work on each down stroke of the drill bit assemblage. Ordinarily these cutting edges do not extend into the zone 28^a. The tooth components 27 occurring in this zone (Fig. 3) do, however, have a shearing action against the walls of the hole and also aid in turning the cutting bit. The components 27 are of minor extent 90 when compared with the full length of the teeth so that any tendency toward retrograde turning of the cutting bit 10 by virtue of the engagement of the components 27 with the walls of the hole on the up stroke will be negated by the far greater turns imparted to the bit by 95 the longer tooth expanses extending under the 100 bit.

It will now be understood that the bezels 25^b of the teeth 25, 25 in striking the solid substances at the bottom of the hole, will react in the direction of arrow 26 (Fig. 3) and cause 105 a turn of the bit 10 at the end of every down stroke of the drill bit assemblage 24, thereby to successively advance the teeth to new positions each time so that successive strokes will occur at different places in the bottom of the 110 holes and so exercise a continuous cutting action.

It is further understood that the teeth 25 are arranged in annular series, that is to say there are teeth all around. When a down stroke is made all of the cutting edges of the teeth are 115 made to strike the bottom of the hole simultaneously. This produces an annular series of spaced cuts.

Reverting to the shoulder formations of the cutting bit 10 and its carrier 9, it is to be observed that the matching shoulders 13, 18 and 120 14, 19 occur below and above the ball annulus 21. The specific purpose of these shoulders is to receive the back thrusts of the cutting bit 10 on each cutting stroke, and thereby to guard the 125 balls 21 against possible shearing as well as to guard the edges of the races 16, 17 from chipping.

Prior mention was made of the downwardly tapering bore 30 (Fig. 1). It will be observed 130 that as the cutting action progresses a core of rock 33, or whatever the earth formation might be, will be built up in the well hole by virtue of the cutting action of the internal cutters 29^d. This core is cylindrical, and being so defines 135 with the tapering bore 30 an annular wedge space 34. Cuttings will continually be falling into this wedge space but during the drilling operation will be washed out by water streams which flow down in the direction of arrow 35 140 and up in the direction of arrow 36.

But when extracting the drill assemblage 24 from the hole the water stream naturally is cut off and cuttings will be permitted to settle and pack in the annular wedge space 34. Some of 145 the cuttings and even large fragments of the core itself will build up across the top ledge 37 which is formed by the upper parts of the filler 3 and the carrier 9.

Now when the tool is extracted from the hole 150

the settled fragments will pack tighter in the annular wedge space 34 by virtue of the tapering walls of the bore 30 and so coact with said walls as to form a grip on the core 33, break it off and carry it up with the tool.

10 Somewhere in the tubing there will be provided a check valve 38 which comprises a pair of leaves which are so hinged at 39 as to enable the leaves to close against the walls of the respective tubing section by gravity. The top of the tubing is secured to a joint 40 of which the coupling pin 41 is a part. This coupling pin will be connected with the standard drill jar and rope socket, which in turn is moved up and 15 down by the walking beam.

18 The action of the check valve 38 simulates the action of the foot valve of a pump. As the apparatus is reciprocated in the well hole, the water and finer cuttings carried thereby will be alternately permitted to pass the check valve and to be lifted thereby. On each down stroke the leaves of the check valve will move toward each other to let the stream past, while on the up stroke the leaves will fall against the walls 25 of the tubing section and lift the superimposed liquid column. The heavier cuttings will gravitate toward the bottom of the tubing string, but inasmuch as these are agitated on every stroke of the drill bit assemblage there will be no possibility of their clogging the mechanism.

28 The operation is readily understood and briefly reviewed as follows: The drilling tool is of the reciprocating type, the tubing being moved up and down in the well hole, a cutting 35 action occurring every time the cutting bit 10 strikes the substance at the bottom.

38 It is when the cutting bit strikes the bottom that it automatically partakes of a turn, the successive turning of the cutting bit being a direct function of the teeth 25 in addition to their 40 function of cutting. By virtue of the fact that these teeth are set on an inclination it is easy to see that the reaction will cause a turn of the cutting bit. The successive turns cause the 45 teeth to strike a new place each time, and inasmuch as the cutting bit 10 is level it follows that all of the active teeth will perform a simultaneous cutting operation at each stroke.

50 The ball annulus 21 is solely relied upon to 55 keep the inserted cutting bit 10 in place, and in order to avoid damaging the balls the impact of the cutting stroke is delivered to the matching shoulders 13, 18 and 14, 19. At this point it is well to observe that the places of contact 6, 5; 8, 11 and 13, 18 become progressively larger toward the bottom of the drilling bit assemblage. The greater portion of the thrusts is thus disseminated before the bottom end 6 of the section 1 is reached. This arrangement avoids 60 damage to the bottom of the drill section.

65 The tapering configuration of the bore 30 enables the drill assemblage to convert its own cuttings into a sample taker. Inasmuch as the core 33 is cylindrical it follows that the annular space 34 will be of a cylindrical wedge shape. Cuttings will settle in this space when the flow

of water is cut off, and these same cuttings will be packed so hard in the space 34 by virtue of the tapering bore 30 when the bit assemblage 24 is reached that they will exercise a grip on the core 33, break it off and bring it to the surface. 80

I claim:—

1. In a reciprocatory drilling apparatus, a cutting bit having a top shoulder, carrier means for the cutting bit with which said bit is interfitted, said carrier means having a bottom shoulder, and a ball annulus between the interfitted portions of the carrier means and bit providing a swivel mount for the bit on the carrier means to prevent the bit from dropping out, said shoulders contacting to receive the thrust of an impact and prevent the shearing of the balls. 85

2. In a reciprocatory drilling apparatus, a drill bit assemblage comprising a cutting bit, means to swivelly support said cutting bit in said assemblage, and teeth on the cutting bit having single bezels all inclined toward a cutting edge at a place of emergence with a substantially upright wall causing a reactive movement of the bit against a solid substance when struck during the downward movement of the assemblage and 100 a responsive turn of the cutting bit on its swivel support. 90

3. In a reciprocatory drilling apparatus, a drill bit assemblage carried by a reciprocable suspending device, said assemblage including a cutting 105 bit, carrier means interposed between the cutting bit and said device from which means the cutting bit is directly suspended, and a ball annulus between the cutting bit and said carrier means, said ball annulus constituting a locking means 110 for the cutting bit.

4. In a reciprocatory drilling apparatus, a drill bit assemblage, said assemblage including a carrier, said carrier having a vertical wall with shoulders at the ends thereof occupying parallel planes, 115 a cutting bit, teeth on the cutting bit having bezels respectively disposed in one direction and thereby subject to a reaction upon striking a solid substance to impart a turn to the cutting bit assemblage in the same direction, a vertical wall included in said cutting bit, said wall fitting inside of the carrier and having shoulders matching those of the carrier, the then confronting walls having matching halves of a ball race, said matching shoulders receiving the impact of a working 125 stroke, and a ball annulus in said ball race comprising with said race the sole support of the cutting bit on the carrier but being guarded against damage on each working stroke by virtue of the engagement of the matching shoulders. 130

5. A reciprocatory drill bit assemblage for wedging a core, said assemblage comprising a toothed cutting bit, a carrier for supporting the cutting bit, and means for swiveling the bit on the carrier, said cutting bit and carrier having 135 a bore tapering downwardly toward an outlet in the cutting bit to define an annular wedge space around a cylindrical core.
